[57] CLAIM

The ornamental design for a chrome faced motorcycle saddlebags, as shown and described.

DESCRIPTION

FIG. 1 is a front elevational view of one of the chrome faced

motorcycle saddlebags with a substantially rectangularly shape showing my new design;

FIG. 2 is a right side elevational view of FIG. 1;

FIG. 3 is a top plan view of FIG. 1;

FIG. 4 is a bottom plan view of FIG. 1;

FIG. 5 is a left side elevational view of FIG. 1;

FIG. 6 is a rear elevational view of FIG. 1;

FIG. 7 is a front elevational view of a substantially U-shaped saddlebag showing a second embodiment of my new design;

FIG. 8 is a right side elevational view of FIG. 7;

FIG. 9 is a top plan view of FIG. 7;

FIG. 10 is a bottom plan view of FIG. 7;

FIG. 11 is a left side elevational view of FIG. 7;

FIG. 12 is a rear elevational view of FIG. 7;

FIG. 13 is a front elevational view of a substantially trapezoidally shaped saddlebag showing a third embodiment of my new design;

FIG. 14 is a right side elevational view of FIG. 13;

FIG. 15 is a top plan view of FIG. 13;

FIG. 16 is a bottom plan view of FIG. 13;

FIG. 17 is a left side elevational view of FIG. 13; and,

FIG. 18 is a rear elevational view of FIG. 13.

The broken lines shown in FIGS. 1, 2, 5, 6, 7, 8, 11, 12, 13, 14, 17, and drawing views are for illustrative purposes only and form no part of the claimed design.
